[57] CLAIM

The ornamental design for a combined vehicle warning
light and reflector therefore, as shown and described.

DESCRIPTION

FIG. 1 is a front perspective view of the combined
vehicle warning light and reflector therefor showing
our new design;

FIG. 2 is a front perspective view of the reflector, the
warning light being omitted for purposes of disclosure;
FIG. 3 is a rear elevational view of the combined light
and reflector; and

FIG. 4 is a side elevational view of the combined light
and reflector.

Fig. 2.
